UNITED STATES PATENT OFFICE.

ARTHUR O. HUBBARD, OF MINNEAPOLIS, MINNESOTA.

FOLDING BOX.

Application filed October 23, 1920. Serial No. 418,971.

To all whom it may concern:

Be it known that I, ARTHUR O. HUBBARD, a citizen of the United States, resident of Minneapolis, county of Hennepin, State of Minnesota, have invented certain new and useful Improvements in Folding Boxes, of which the following is a specification.

The object of my invention is to provide a folding box of stronger and more durable construction, though corresponding in general appearance and manner of folding to the box shown and described in Letters Patent of the United States, issued to me on the 28th day of June, 1898, No. 606,459.

Other objects of the invention will appear from the following detailed description.

The invention consists generally in various constructions and combinations, all as hereinafter described and particularly pointed out in the claims.

In the accompanying drawings forming part of this specification,

Figure 1 is a perspective view of a folding box embodying my invention,

Figure 2 is a similar view, showing the box partially folded,

Figure 3 is a horizontal sectional view of one of the end walls,

Figure 4 is a vertical sectional view showing the manner of mounting the reinforcing or bracing wires in the walls of the box.

Figure 5 is a detail view of one of the hinges connecting the side and end walls of the box,

Figure 6 is a detail sectional view of the same.

In the drawing, 2 represents the side walls of the box, composed of thin panel-like material arranged in strips, running lengthwise of the box and placed edge to edge from the bottom to the top. 3 and 4 are top and bottom rails, made of thicker, heavier material and 5 and 6 are the end rails, having tenons at the ends fitting mortises in the ends of the top and bottom rails. The end walls have panels 2^a, top rails 3^a and bottom rails 4^a and are also equipped with vertical end rails 5^a and 6^a, mortised to the top and bottom rails. The side and end walls are pierced vertically to receive reinforcing and bracing wires 7 which are bent so that their ends are in parallel relation and pass down through the top rails and upon opposite sides of the panels 2, the lower ends of the wires penetrating the bottom rails to a point near the bottom

and having their ends outwardly turned and locked in the rails.

These wires 7 not only hold the panels with their edges in alignment, but unite the upper and lower rails of the box and prevent the panels from working out of the grooves in the end rails. Loops 8 are provided, herein shown as fitting between the abutting longitudinal edges of the panels for holding the ends of the wires in parallel relation and clamping them firmly against the faces of the panels. It will be understood, however, that these loops are placed by a machine equi-distant apart and some of them may be in the joints between the sections of the panels, as shown, but some of them may be mounted in the sections of the panels themselves. The function, however, of the loops is the same in both cases. The panels are thereby held securely against

sliding or slipping, either vertically or horizontally, and at the same time are free to yield slightly under pressure and are therefore in less danger of being broken when handled roughly or when the box is heavily loaded. The ends of the panels are seated in grooves provided in the upright rails.

The loops 8 are preferably formed of wire that is inserted between or through the sections of the panels and bent around the reinforcing wires, as indicated in Figure 3, to form an eye or loop. The side and end walls are of substantially the same structure as far as reinforcing is concerned and the description above will suffice for both walls of the box.

For connecting the side and end walls I prefer to employ the following construction. 9 and 9^a represent metallic strips, folded into U-shape form and fitting the ends of the walls at the top and bottom and secured thereto by suitable rivets 10, which are inserted through the rails at the top and bottom. The straps 9 are of sufficient length to bridge the joints between the horizontal and vertical rails of the walls and brace and strengthen the box at this point, and shorter straps 11 and 11^a are also provided, secured to the vertical rails in the manner described intermediate to the top and bottom rails. For smaller boxes the straps 11 and 11^a may be omitted.

For joining the opposite straps together to form a hinge, staples 12 are provided having their ends inserted through holes 13 in

the rounded portion of the straps and then folded or bent to lie on the inner surface of the straps and lock the staple therein. These staples are so arranged that their loop 5 portions will lie in different planes substantially at right angles to one another and permit freedom of movement of the walls one upon the other. The diagonally opposite rails 6 of the side walls have offsets 6^b 10 therein and straps 9^b are fashioned to fit these offsets so that when the box is folded a space will be formed between the opposite side and end walls to receive the bottom plate 14 that is hinged to one of the side 15 walls and is free to drop down to a horizontal position between the walls and close the bottom when the box is unfolded or set up.

As compared with the box of my former 20 patent, above referred to, it will be noted that substantially horizontal and upright rails are provided at the top and bottom and the corners of the box, the joints connecting these rails being strengthened by metallic 25 reinforcement, while the panels between the rails are braced and strengthened by the vertically arranged reinforcing wires. A box of this construction is therefore stronger and more durable than the one described in 30 my former patent while the general principle of folding and hinging the bottom of the box is embodied in both constructions.

I claim as my invention:

1. A folding box comprising side and end 35 walls, each wall composed of top and bottom and end rails secured together and an intermediate panel of comparatively thin material and made up of a plurality of narrow strips placed edge to edge, reinforcing 40 wires passing vertically through the top and bottom rails and upon opposite sides of said panel strips, and loops connecting the wires on opposite sides of the panel.

2. A folding box comprising side and 45 end walls having upper and lower and end rails mortised together, a panel composed of comparatively thin narrow strips fitting between said upper and lower and end rails, reinforcing wires bent to form loops inserted 50 vertically through said upper and lower rails upon opposite sides of said strips, the lower ends of the wires being locked in the lower rails and wire loops connecting at

intervals the opposite portions of the wires through the walls of the box. 55

3. A folding box comprising side and end walls having upper and lower horizontal rails and vertical end rails between them, metallic strips, U-shaped in form, fitting the ends of said walls and bridging the 60 joints between the upper and lower and end rails and secured to said rails, and staples having their end portions mounted in said strips and their looped portions intermediate to form a hinged connecting means 65 between the opposite strips.

4. A folding box comprising side and end walls having upper and lower rails and U-shaped straps fitting the ends of said walls and secured thereto and bridging the 70 joints between the end rails and said upper and lower rails, and hinge connections between the opposite straps.

5. A box comprising side and end walls, each wall composed of top and bottom and 75 end rails secured together and composed of comparatively thick material, and an intermediate panel made up of a series of strips of comparatively thin material placed edge to edge, reinforcing wires passing vertically 80 through holes in said top and bottom rails upon opposite sides of said panels and seated snugly against the surfaces of said panels, and loops passed around said wires and extending through the joints between 85 said strips and connecting the wires on one side of said panel with the corresponding wires on the opposite side.

6. A box comprising side and end walls having upper and lower and end rails secured together, a panel composed of strips of thinner material than said end rails placed edge to edge with the ends of said strips seated within vertical grooves in the end rails of said walls, reinforcing wires passing vertically through said top and bottom rails upon opposite sides of said panel strips and having their ends anchored in said rails and loops connecting said wires through said panels and drawing said 100 wires snugly against the surfaces of said panel.

In witness whereof, I have hereunto set my hand this 6th day of October, 1920.

ARTHUR O. HUBBARD.
